UNITED STATES PATENT OFFICE.

FRANCIS J. BRITTON, OF BRAINERD, MINNESOTA, ASSIGNOR OF ONE-HALF TO CLARA GILMER, OF BRAINERD, MINNESOTA.

SUPPORT FOR NURSING BOTTLES.

Application filed December 10, 1923. Serial No. 679,749.

This invention relates to a support for nursing bottles, which is adapted to be secured to the side of a baby carriage, crib or the like.

5 The principal object of the invention is to provide a device of this kind which includes a plurality of joints which are universally adjustable, so that the bottle may be swung bodily in any direction desired, and 10 may also be disposed at any desired angle with respect to the supporting device.

It is also an object of the invention to provide frictional devices for the joints, so 15 that the bottle will normally remain in the position to which it is adjusted, but may be moved by the baby to any other position whenever desired, and the tension of the frictional connections is preferably made 20 adjustable so as to adapt it to the strength of the baby, or to other conditions under which the device may be used.

25 The invention also includes improved means for detachably holding the bottle, so that it may be easily removed for cleaning or refilling.

30 The nature of the invention and the principles embodied therein will be best understood from the following detailed description taken in connection with the accompanying drawing, which illustrates the preferred form of the invention.

In the drawing:

35 Figure 1 is a perspective view of a portion of a carriage having my invention attached thereto.

Figure 2 is an enlarged perspective view of the invention.

40 Figure 3 is a sectional view of the supporting bracket and the adjustable tensioning device.

Figure 4 is a sectional view illustrating in detail the means for attaching the bottle.

45 Figure 5 is a sectional view illustrating in detail one of the joints.

Figure 6 is a detail perspective view of the member against which the bottle is held.

50 The invention as illustrated includes a bracket or clip 10, of a size and shape to embrace one of the rails 11 of the carriage, and this bracket is provided with one or more pairs of opposed holes 12 for receiving a bolt 13, by means of which the bracket is secured to the rail. The bracket 10 has an upwardly extending socket 14, in which is

secured a stem 15 having a reduced neck 16 terminating in a spherical head 17.

The member against which the bottle 18 is held includes an arcuate seat 19, which partially encircles the bottle and has an outwardly extending socket 20, in which is suitably secured a stem 21 having a neck portion 22 terminating in a spherical head 23, similar to the head 17, and connected with and supported therefrom in a manner to be hereinafter described.

65 The socket 20 and stem 21 are provided on opposite sides with threaded recesses 24, adapted to receive screws 25, which serve to secure the ends of a band which encircles the bottle and supports it against the seat 19. This band includes one or more elastic strips 26, to the ends of which are secured suitable tabs 27 and 28 of pliable material, such as leather, and which have secured thereto bearing plates or washers 29 and 30. These washers are provided with holes 31 and 32 for receiving the retaining screws 25, and one of the holes, as 32, is preferably made large enough so that it may be passed over the head of the respective screw 35. This enables the tab 28 to be easily detached for convenience in removing or attaching the bottle to the support, and when the bottle is in place, as shown in Figures 2 and 4, the tension of the elastic strips 26 holds the washer 32 firmly underneath the upper edge of the screw head.

70 The heads 23 and 17 are connected by a pair of clamping bars 33, which are held together by a plurality of bolts 34, and the inner sides of the bars are formed with opposed rabbets 35 having spherical recesses 36 for receiving opposite sides of the respective spherical heads 23 and 17. The bolts 34 are provided with thumb nuts 37, which may be turned to adjust the tension of the engagement between the bars and the respective heads 23 and 17, and thereby vary the amount of force which is necessary to adjust the angle between the bars 33 and the respective stems 14 and 20, or to rotate the stems axially in the recesses 36.

75 It will be readily understood that the nuts 37 may be adjusted so as to obtain any desired frictional resistance between the spherical heads 23 and 17, and the recesses 36 in which they rotate. When so adjusted, the bottom may be swung bodily in any

- direction desired, and may also be turned on its axis. It will then remain in that position until acted upon by some external force, and yet the frictional resistance of the joints will 5 not be sufficient to cause possible injury to the baby, since in case he should fall or throw himself against any part of the bottle or holder the joints will yield. Between feeding times, the bottle may be swung to 10 the position shown in dotted lines in Figure 1, and may conveniently be removed from the holder by disengaging the eye 32 from the head of the screw 25, underneath which it is held.
- 15 While I have shown and described the various parts of the device in rather minute detail, it is, of course, to be understood that this is merely illustrative, and that many modifications may be made in the relative 20 size, shape and general arrangement of various parts without departing from the salient features of the invention as expressed in the claims.
- What is claimed is:
- 25 1. A support for bottles and the like, comprising a curved seat for receiving the bottle and having an outwardly extending socket, a stem mounted in and projecting from the socket and having a spherical head 30 at its outer end, headed elements securing said stem in the socket, an elastic band adapted to embrace the bottle and holding the same on its seat, said band having eyes near its ends for engagement with the heads
- of said headed elements, a pair of clamping bars having opposed spherical recesses for receiving said spherical head, and means for adjusting said bars to increase or decrease the friction between the bars and said spherical head. 35
2. A bottle support comprising a bracket, a seat for the bottle supported for universal adjustment with respect to said bracket, and means for retaining a bottle against said seat, said retaining means including an elastic band adapted to encircle the bottle and provided near its ends with eyes, screws passing through the eyes and secured to the seat, one of the screws having a head smaller than the eye so that the end of the band may be 40 easily detached therefrom for changing the bottle. 45
3. In combination, a curved seat adapted to partially encircle a bottle, a socket extending outwardly from the seat, a stem in said socket, means for supporting the stem for universal adjustment, screws extending outwardly from said socket and securing the same to the stem, a flexible band adapted to partially encircle the bottle and to hold the same against said seat, said band having holes near its ends for engagement with the heads of said screws. 50
- In testimony, that I claim the foregoing as my own, I have hereto affixed my signature. 55

FRANCIS J. BRITTON.
